(57) **CLAIM**

The ornamental design for a bag toss game target, as shown.

DESCRIPTION

FIG. 1 is a top, front perspective view of a bag toss game target showing my new design, with the support arm shown in a collapsed position;

FIG. 2 is a bottom, rear perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a sectional view taken along line 9-9 of FIG. 5;

FIG. 10 is a top, front perspective view thereof, with the support arm shown in an extended position;

FIG. 11 is a bottom, rear perspective view of FIG. 10;

FIG. 12 is a top plan view of FIG. 10;

FIG. 13 is a bottom plan view of FIG. 10;

FIG. 14 is a front elevational view of FIG. 10;

FIG. 15 is a rear elevational view of FIG. 10;

FIG. 16 is a right side elevational view of FIG. 10;

FIG. 17 is a left side elevational view of FIG. 10; and,

FIG. 18 is a sectional view taken along line 9-9 of FIG. 14.
